CLAIM

The ornamental design for a golf tee, as shown and described.

DESCRIPTION

FIG. 1 is a side view of a golf tee in a fully extended position showing my new design;

FIG. 2 is a side view of the golf tee of FIG. 1 in a fully contracted position;

FIG. 3 is a side view of the golf tee of FIG. 1 in an intermediate position;

FIG. 4 is a bottom view of the golf tee of FIG. 1;

FIG. 5 is a top view of the golf tee of FIG. 1;

FIG. 6 is a side view of a second embodiment of the golf tee of FIG. 1 in a fully contracted position; and,

FIG. 7 is a side view of the golf tee of FIG. 6 in a fully extended position.

The golf tee is rotationally symmetric about its vertical axis.
